UNITED STATES PATENT OFFICE.

CLIFFORD G. PEPPER, OF PITTSBURG, KANSAS.

HOLDER FOR RIVETING-TOOLS.

1,283,886.

Specification of Letters Patent.

Patented Nov. 5, 1918.

Application filed March 27, 1918. Serial No. 225,019.

To all whom it may concern:

Be it known that I, CLIFFORD G. PEPPER, a citizen of the United States, residing at Pittsburg, in the county of Crawford and State of Kansas, have invented certain new and useful Improvements in Holders for Riveting-Tools, of which the following is a specification, reference being had to the accompanying drawings.

10 This invention relates to pneumatic riveting devices, and particularly to means whereby the hammers may be held to the work or whereby an anvil may be held against the head of the rivet.

15 The general object of this invention is the provision of a holder for riveting hammers provided with relatively strong electro-magnets which will act to hold the hammer to the work and support it.

20 A further object is the provision in connection with the electro-magnets which engage the work, of springs and yokes, the yokes embracing the pneumatic riveter and the springs engaging the yokes so as to give 25 a certain amount of necessary play or movement to the riveter or hammer.

25 A further object is to provide a holder of the character described, which may also be used for holding an anvil with the usual 30 rivet snap against the rivet head.

The advantage of this device is that it permits one man to operate the hammer instead of two, as is at present the case.

35 Other objects will appear in the course of the following description.

My invention is illustrated in the accompanying drawings, wherein:—

Figure 1 is an elevation of a pneumatic hammer equipped with my improved holding device;

Fig. 2 is a section on the line 2—2 of Fig. 1;

Fig. 3 is an elevation of an anvil with my improved means for holding it to the work.

40 Fig. 4 is an elevation showing how my improved hammer and anvil holder are to be used.

45 In Fig. 1, I show a pneumatic riveter of ordinary type and designated 10. I do not show the details of this pneumatic riveter, as riveting hammers of this character are well known and form no part of my invention. The casing of the riveter is provided intermediate its ends with a shoulder or flange 11. My holder comprises a yoke designated generally 12 and formed of two

semi-circular steel bands 13, approximately 2" wide and $\frac{3}{8}$ " in thickness, these bands being joined to each other as at 14 by bolts or other suitable means and being provided at 60 their joined ends with the hooks 15, the bills of the hooks extending forward and inward.

Used in connection with the yoke 12 is a yoke 16 or brace which is also formed to loosely embrace or surround the casing of 65 the pneumatic riveter adjacent its work engaging end, and this brace or yoke 16 is formed with two circular extensions 17 disposed to engage around and support the electro-magnets 18 which may be of any 70 suitable character, but are intended to exert a relatively great pull. Eye-bolts 19 are engaged with the cores of these magnets and engaged with these eye-bolts are the coiled contractile springs 20 having rings 21 at 75 their ends which in turn are engaged with the bills of the hooks 15.

The wires 22 from the electro-magnets extend to a switch box 23 and from the switch box extends the wire 24 which connects with 80 any source of electricity. The switch box is provided with a switch whereby an electric circuit may be established through the magnets or cut off. Any suitable switch may be used for this purpose.

85 Preferably, in order to provide for the attachment of the eye-bolts 19, the core of each electro-magnet is bored out, the bore being $1\frac{1}{2}$ " wide at the inner end and 1 inch in diameter at the top and $1\frac{1}{4}$ " deep with ordinary sizes of magnets and this space is to be filled with non-conducting metal, such as babbitt. A hole is then drilled into this filling or plug 95, this hole being interiorly screw-threaded and the eye-bolts 19 engaging with these screw-threads.

Where this holder is used in connection with a pneumatic riveter the yoke 12 is disposed around the body of the riveter adjacent to the flange 11 and bearing thereagainst 100 with the yoke 16 engaging loosely around that portion of the riveter adjacent the rivet to be driven. Under these circumstances, when the magnets 18 are energized they will magnetically engage with the work A and 105 the hammer may then be operated in the ordinary or usual manner to cause the rivet snap 26 to overturn the head of the rivet B. When the holder is in place with the magnets engaged with the work, the springs 20 110 may be expanded by drawing the pneumatic riveter outward so as to permit the head of

the piston or hammer of the riveter to be disposed against the extremity of the rivet. These springs will then cause the body of the riveter to move inward as the rivet is over- turned.

When it is desired to use my yoke and magnets as a "holder on", that is, to provide means for holding an anvil against the head of the rivet while its opposite end is being turned down, I dispose within the yoke 12, 10 an anvil consisting of a bar of iron or other metal designated 27. In ordinary practice this metal bar will be about $2\frac{1}{4}$ " in diameter and have a handle at one end. This bar is 15 also provided with a shoulder 28 and a socket for the shank of the rivet snap 29. This rivet snap fits over the rivet head and is used for the purpose of correctly forming and finishing the rivet head. By using two of these 20 holding devices, one holding the anvil and the other the hammer, it is obvious that the rivet may be driven or overturned by a hammer held in position by means of one yoke and the anvil be used to engage the head of 25 the rivet on the other side of the rivet or work.

By using my device only one man is needed to operate the hammer or pneumatic riveter on one side of the work and one man to 30 operate the anvil on the opposite side of the work thus using only two men where to-day four men are ordinarily used, two to operate the riveter and two to support and hold the anvil. It will be seen that the magnets hold the anvil up to place instead of it 35 requiring two men pushing with all their strength against the riveter to hold it to the work. Furthermore my device relieves the operator from much of the vibrations and 40 nerve-racking strain incident to the operation of a pneumatic riveter.

Having described my invention, what I claim is:

1. A holder for riveting tools including an 45 electro-magnet, a yoke adapted to operatively engage the tool, and a spring disposed between the electro-magnet and the yoke urging the yoke toward the magnet when the spring is under tension.

50 2. The combination with a riveting tool including an outer casing, of a plurality of magnets coacting with the casing and adapted to engage the work and resiliently yieldable connections between the electro-magnets

and the riveting tool urging the riveting 55 tool against the work but permitting it to be shifted outward from the work and relative to the electro-magnet.

3. A device of the character described including a pair of electro-magnets, a yoke 60 connecting said magnets and adapted to engage around a riveting tool, a second yoke adapted to engage around the riveting tool and abut against a portion thereof, and contractile springs disposed between the electro- 65 magnets and the second named yoke and operatively engaging the same.

4. A device of the character described including a plurality of electro-magnets adapted to engage the work, a yoke operatively 70 engaging the electro-magnets and formed to embrace a riveting tool, a second yoke formed to embrace the riveting tool and to abut against a portion thereof, said second named yoke having hooks at its ends, and contractile 75 springs operatively engaging the cores of the magnets and the hooks and yieldingly resisting outward movement of the riveting tool away from the work.

5. The combination with a riveting tool 80 having a shoulder intermediate its ends, of a yoke surrounding the riveting tool and abutting against the shoulder and having hooks at its ends, a second yoke operatively engaging the riveting tool, a plurality of 85 electro-magnets operatively engaged with the second named hook and adapted to engage the work, a pair of contractile springs operatively engaged with said magnets and with said hooks, and electrical connections 90 from the magnets including a switch.

6. A device of the character described including a plurality of electro-magnets each having a core, a dove-tailed plug inserted in each core and formed of non-conducting 95 metal, eye-bolts engaging said cores, a yoke adapted to embrace a riveting tool and operatively embracing the magnets, a second yoke formed to embrace the riveting tool, 100 springs engaging said eye bolts and said hooks, and electrical connections from the magnets including a switch.

In testimony whereof I hereunto affix my signature in the presence of two witnesses.

CLIFFORD G. PEPPER.
